UNITED STATES PATENT OFFICE.

HANS STARCKE, OF ELBERFELD, GERMANY.

APPARATUS FOR RECORDING TELEPHONIC MESSAGES OR SOUNDS.

No. 825,496.

Specification of Letters Patent.

Patented July 10, 1906.

Application filed February 14, 1905. Serial No. 245,635.

To all whom it may concern:

Be it known that I, HANS STARCKE, a citizen of the German Empire, residing at Elberfeld, Germany, have invented certain new and useful Apparatus for Use in Recording Telephonic Messages or Sounds, of which the following is a specification.

In apparatus hitherto known for recording telephonic messages or sounds on a phonograph-cylinder without any assistance of the speaker the recording was limited to a single drum, so that only a limited amount of conversation could be recorded in this way. This drawback is obviated by the present invention by a series of phonograph-cylinders being successively brought into the desired recording position by an automatic apparatus, hereinafter described, the beginning and the end of the throwing into gear of the cylinders being notified to the users by the ringing of a bell in proximity to the mouthpiece or diaphragm of the receiver, so that the conversation may be recorded without any gaps.

A construction of the apparatus according to this invention is illustrated, by way of example, in the accompanying drawings, in which—

Figure 1 is a longitudinal section through a switching apparatus according to this invention. Fig. 2 is a plan; Fig. 3, a cross-section on the line A A seen in the direction of the arrow. Fig. 4 shows the connection-diagram; Fig. 5, the arrangement of change-wheels. Fig. 6 shows the ratchet-gear of the carriage. Figs. 7 and 8 illustrate the mechanism for stopping the changing of the cylinders; and Figs. 7^a and 8^a are top plan views of Figs. 7 and 8, respectively. Fig. 9 illustrates the signaling of the change.

The arrangement and the working of the apparatus are as follows:

When the apparatus is to be used, electromagnets c and d are connected to the telephone-line b by means of switches a. The first electromagnet operates in the well-known manner the needle e, recording the conversation on the cylinder, the second magnet attracting, when current passes through it, a lever-armature g, provided with ratchet-teeth and pivoted at f, Fig. 6, thus releasing a pawl i, secured to the carriage h. When the circuit is broken, the ratchet-teeth under the influence of a spring k come again into the path of the pawl i, so that if the carriage moves in the direction of the arrow v, Fig. 2—

that is to say, advances—it can be stopped at any moment, while if the carriage moves in the direction of the arrow r—that is to say, backward—the pawl i slides over the teeth, 60 so that the return movement is independent of the current. The movement of the carriage is effected by means to be hereinafter described.

A toothed wheel m, Fig. 1, mounted on a spindle l, is rotated by a clockwork (not shown in the drawings) and transmits its rotation in the position shown in Fig. 1 by means of wheels n and o to a screw-spindle p, serving to drive the carriage h—that is, to 70 advance the carriage in the direction of the arrow v. When the carriage h nears the end of its travel, the projection q upon it strikes a fork t, pivoted at s, which, by means of a fixed sleeve or projection u, causes the spindle l to 75 move in longitudinal direction. Owing to this movement of the spindle l, the rotation of the wheel m is transmitted to the spindle p by means of the wheels w, x, and y, whereby, as will be seen from the directions shown by arrows in Fig. 5, the spindle p will be caused to rotate in the opposite direction, thus effecting the return of the carriage in the direction of the arrow r. At the end of the return movement a perfectly similar device q' s' t' u' 80 will again change the direction of rotation of the spindle p. The rotary movement communicated by the wheel m to the spindle l is transmitted by toothed wheels 1 and 2 to a spindle 3, carrying the phonograph-cylinder, 85 which is caused to rotate. As the cylinder-supporting frame 4 5 is supported by the carriage h, the cylinders not only rotate, but move longitudinally also at the same time, which movements must also be followed by 90 the transmission-wheel 1. To that end the wheel 1 is mounted on the spindle l by means of a feather-key sliding in the groove 6, the shifting during the advance being effected by a spring 7, secured to the carriage h, while 100 during the return the driving is effected by a projection 8 on the carriage. When the carriage has reached the end of its advance, a change takes place by the shifting of the wheel 1. During that change the part u 105 strikes the toothed wheel 1 and by overcoming the spring 7 shifts the latter, thus disengaging it from the wheel 2. The shifting of the spindle l releases also for a moment a disk 9, forming the support for the cylinders 110 and arranged on the cross-wall of the carriage, as will be understood on examining

Figs. 7 and 8. During the advance of the carriage the part 10, mounted on the spindle 1, is in the path of the disk 9, so that the latter is thereby prevented from rotating. On the above-described movement of the spindle 1 the locking of the disk is released, so that the disk can freely move longitudinally and is locked again on reaching the part 12. The release of the disk 9 and of the toothed wheel 2 enables the cylinder-supporting frame 4 to be turned in the support 5 by means of an automatically-winding steel band 13. When the next cylinder has been brought in this way into position, the spindle 3 of the roller 15 is again arrested by the disk 9, as in the meantime the part 12 has come into the path of the said disk, and thus prevents it from rotating further. During the return of the carriage 11 the toothed wheel 1 after the removal 20 of the part 14 and under the action of the spring 7 is immediately caused to engage with the wheel 2, mounted on the spindle of the cylinder. By means of a pawl-gear 21, mounted on the frame and clearly shown in Fig. 2, the steel band 13 is prevented from becoming unwound, so that, the disk 9 forming an abutment against which the spindle 3 is held, the phonograph-cylinder is supported in a sufficiently rigid manner. On the shifting 25 of the spindle 1, which takes place at the end of the return movement of the carriage, the disk 9 must remain locked on the portion 11, so that another change of cylinder may not take place. To this end a second ratchet-gear 15, pivoted at 14 to the longitudinal wall of the carriage, is provided, which ratchet-gear is released during the advance of the carriage, as shown in Fig. 7. On the movement of the spindle taking place at the 30 end of the advance movement as soon as the part 12 comes into the path of the disk 9 the ratchet-gear 15 is turned, by means of the part 10 and an arm 16, into the locking position. (Shown in Fig. 8.) On the backward shifting of the spindle the release of this locking-gear is effected by the part 12, which acts on the pivoted arm 17 as soon as the part 10 has again come into the path of the disk 9. The beginning and the end of the change 35 are notified to the speaker by a bell operated by pins 18 19, mounted on the carriage 11, which strike the lever 20 of the bell-hammer, which is thus oscillated, the pins striking the tooth-shaped projections of the lever 20. The number of projections encountered by the pins 18 or 19 and the number of the strokes of the bell caused thereby can be used for distinguishing the beginning and the end of the change of cylinders. The sounds of the bell, amplified, if desired, by a sound-board, are projected from as near as possible onto the diaphragm of the receiver and thence conveyed through the telephone-line in the well-known manner 45 to the ear of the person at the transmitter.

What I claim as my invention, and desire to secure by Letters Patent, is—

1. Apparatus for phonographically recording telephonic messages, comprising a plurality of phonograph-cylinders, a plurality of 70 radial rods supporting said cylinders and means for simultaneously rotating and effecting the transverse movement of the recording-cylinders as they come into operative position substantially as set forth. 75

2. Apparatus for phonographically recording telephonic messages, comprising a plurality of phonograph-cylinders, a plurality of radial rods supporting said cylinders and means for simultaneously rotating and effecting the transverse movement of the recording-cylinders as they come into operative position, in combination with a device for starting and stopping the apparatus substantially as set forth. 80

3. Apparatus for phonographically recording telephonic messages comprising a plurality of phonograph-cylinders, a plurality of radial rods supporting said cylinders and means for simultaneously rotating and effecting the transverse movement of the recording-cylinders as they come into operative position, in combination with means for reversing the transverse motion of the cylinders and an electrically-operated device for 95 starting and stopping the apparatus substantially as set forth. 90

4. In an apparatus for phonographically recording telephonic messages means for simultaneously rotating and effecting the 100 transverse movement of the recording-cylinder comprising a clockwork - driven shaft, toothed wheels mounted thereon, cylinder-supporting rods driven from said shaft, a worm - shaft driven from said shaft and 105 a frame - supporting carriage transversely moved by said worm-shaft substantially as set forth.

5. In an apparatus for phonographically recording telephonic messages, means for 110 simultaneously rotating and effecting the transverse movement of the recording-cylinder comprising a clockwork-driven shaft 1, toothed wheels 1 and n mounted thereon, cylinder-supporting rods 3 driven from said 115 shaft, a worm-shaft p driven from said shaft and a frame-supporting carriage 11 transversely moved by said worm-shaft substantially as set forth.

6. In an apparatus for phonographically 120 recording telephonic messages, means for starting and stopping the motion of the apparatus comprising an electromagnet, a pivoted spring-operated armature-rack and a pawl carried by the carriage substantially as 125 set forth.

7. In an apparatus for phonographically recording telephonic messages, carriage-driving mechanism, reversal-of-motion gearing therefor, projections on the front and rear 130

- of the carriage, pivoted levers operated thereby and collars on the shaft of the motion-reversal gearing operated by said levers, substantially as set forth.
5. 8. In an apparatus for phonographically recording telephonic messages, a device for automatically bringing successive cylinders into recording position, comprising a frame, radial cylinder - supporting shafts carried thereby, a spring-band surrounding said frame and an engaging and releasing mechanism for said shafts substantially as set forth.
10. 9. In an apparatus for phonographically recording telephonic messages, a device for automatically bringing successive cylinders into recording position comprising a frame, radial cylinder - supporting shafts carried thereby, a spring - band surrounding said frame, a toothed disk engaging said shafts and collars engaging said disk substantially as set forth.
15. 10. In an apparatus for phonographically recording telephonic messages, a device for automatically bringing successive cylinders 20 into record position comprising a frame 4, 5, radial cylinder-supporting shafts 3 carried thereby, a spring-band 13 surrounding said frame, a toothed disk 9, engaging said shafts, collars 10, 12 engaging said disk, and a disk-locking device 15, 16, 17, operated by said collars substantially as set forth.
25. 11. In an apparatus for phonographically recording telephonic messages, a device for automatically bringing successive cylinders
- into recording position comprising a frame, radial cylinder - supporting shafts carried thereby, a spring-band surrounding said frame, a toothed disk engaging said shafts, collars engaging said disk and a disk-locking device operated by said collars substantially as set forth. 30
11. In an apparatus for phonographically recording telephonic messages, a device for automatically bringing successive cylinders 35 into record position comprising a frame 4, 5, radial cylinder-supporting shafts 3 carried thereby, a spring-band 13 surrounding said frame, a toothed disk 9, engaging said shafts, collars 10, 12 engaging said disk, and a disk-locking device 15, 16, 17, operated by said collars substantially as set forth. 40

In testimony whereof I have signed my name to this specification in the presence of two subscribing witnesses.
